ORE REDUCING MACHINE

Harlowe Hardinge, York, Pa.

Application May 16, 1934, Serial No. 725,847

6 Claims. (Cl. 83—46)

This invention relates to ore reducing machines.

More particularly the invention relates to ore reducing machines of the type comprising a 5 rotatable drum having a considerable diameter and comparatively narrow width.

The drum of an ore reducing machine of this type has a plurality of material elevating means or buckets arranged around the inside periphery 10 thereof for the purpose of elevating the ore or other material to a considerable height.

The drum is also so constructed as to confine the ore undergoing reduction to a relatively narrow zone. In this way the grinding or disinterring 15 15 grating of the ore is done in a closed circuit.

Disposed within the drum, preferably adjacent the bottom portion thereof, are stationary impact means. The impact means may be in the form of a plurality of plates which are 20 located in the path of the falling ore discharged from the elevating means.

The impact means are usually so disposed and constructed as to support a comparatively shallow bed of crushed or disintegrated ore. 25 This shallow bed of ore on the impact means absorbs the shock of the oncoming ore and thereby prevents excessive or undue wear of the plates which constitute the impact means.

Furthermore, in ore reducing machines of this 30 type, means are usually provided for classifying the ore so that the fines are continuously removed from the machine as new or fresh material is delivered thereto. Fluid classifying means, either in the form of air or water, have 35 been used for classifying purposes.

In the case where water is used for classifying the pulverized ore, the fines are floated off through a suitable discharge launder.

According to the methods heretofore employed 40 for removing the fines, the ore remained in the grinding circuit until reduced to fines which would float off with the water or other classifying medium. This has retarded the productive capacity of the machines, since many of the fines which otherwise would have been removed from the grinding circuit, remained in the grinding circuit along with the coarser particles of ore undergoing reduction.

By the present invention a new method of 50 classifying the ore has been devised so as to hasten the removal of the fines and thereby increase the productive capacity of the machine.

An object of the invention is to provide an 55 improved ore reducing machine with which is

combined a separate means for classifying the ore.

Another object of the invention is to provide an improved ore reducing machine in which the ore first discharged from the elevating means 5 of the machine is intercepted by a grizzly or screening device which separates the coarser particles from the fines and returns the coarser particles to the machine for further reduction, and in which means are provided for delivering 10 the fines to a device disposed outside of the ore reducing machine and adapted to further classify the finer particles of the ore.

Another object of the invention is to provide an improved ore reducing machine in which the 15 drum of the machine is mounted in a flexible cradle adapted to move with irregularities in the shape of the drum as it rotates.

Another object of the invention is to provide an improved means for rotatably supporting 20 and driving the drum of an ore reducing machine in which irregularities both in the motion of the drum and the driving means are taken care of.

Another object of the invention is to provide 25 an improved ore reducing machine in which means are provided for removing excess material from the machine in excess of a predetermined amount, so as to reduce the power consumption and frictional wear on the inside of 30 the drum of the machine.

Another object of the invention is to provide 35 an improved ore reducing machine in which means are provided for removing the ground and partly ground material at an elevation sufficiently high above the bottom of the machine so that the withdrawn material can be classified and the oversize returned to the mill by gravity.

Another object of the invention is to provide 40 an improved classifying system for ore reducing machines of the above type in which means are provided within the machine for partially classifying the material and additional classifying means are provided outside of the machine for the final classification of the material so as to 45 improve the character of the product produced and increase the efficiency of the machine.

Another object of the invention is to provide 50 an improved ore reducing machine in which means are provided for maintaining the load within the machine within the confines of the elevating means.

Another object of the invention is to provide 55 an improved ore reducing machine of the character mentioned, which is simple in construc-

tion, and reliable and exact in function under all conditions of service.

The invention also comprises certain new and useful improvements in the construction, arrangement and combination of the several parts of which it is composed, as will be hereinafter more fully described and claimed.

In the accompanying drawings:—

Figure 1 is an end elevation partly in section of an ore reducing machine embodying the invention;

Figure 2 is an elevator of the machine shown in Fig. 1, looking at the driving mechanism;

Figure 3 is a plan of the structure shown in Fig. 1;

Figure 4 is an enlarged plan of the take-off grizzly;

Figure 5 is a section taken on the line 5—5 of Fig. 4;

Figure 6 is a detail section of one of the buckets, taken on the line 6—6 of Fig. 1;

Figure 7 is a detail of a portion of the drum supporting cradle;

Figure 8 is a section taken on the line 8—8 of Fig. 7;

Figure 9 is a vertical section taken on the line 9—9 of Fig. 1, and

Figure 10 is a section taken on the line 10—10 of Fig. 9 and showing the manner of supporting the drum supporting cradle.

While I have shown only the preferred form of the invention; it should be understood that various changes or modifications may be made within the scope of the claims hereto attached without departing from the spirit of the invention.

Referring to the drawings, the improved ore reducing machine may comprise a drum 11 having an annular peripheral wall 12 and opposite end flanges 13 and 14 which depend from the wall 12. As shown by Figs. 1 and 2, the thickness of the drum is comparatively narrow with respect to the diameter thereof.

The wall 12 and flanges 13 and 14 of the drum 11 are preferably constructed from sheet material, such as plate steel of suitable gauge, the adjoining edges thereof being fastened together to form a water tight structure by any suitable method, such as welding.

The end flanges 13 and 14 of the drum 11 are in the nature of annular rings and are open at the center, as shown in Fig. 1. In this way a certain amount of water may be accommodated in the bottom portion of the drum for a purpose to be hereinafter more fully described. The water is fed into the drum 11 through a suitable pipe 15.

Arranged around the interior of the peripheral wall 12 of the drum 11 and confined between the end flanges 13 and 14, is an annular series of buckets 16.

As shown in Figs. 1 and 6, each bucket 16 consists of a rectangular piece of sheet material, such as plate steel, the side edges 17, 18 of which are fastened to the end flanges 13, 14, respectively, and the rear edge 19 thereof being fastened to the peripheral wall 12 of the drum, by any suitable method, such as welding, as indicated at 20, Fig. 6.

The sheet of plate steel forming the bottom of each bucket 16 projects inwardly from the wall 12 of the drum 11 and is inclined in the direction of travel, as shown in Fig. 1. In this way the buckets constitute pockets for containing a suitable quantity of ore or other material, said pockets being wider at their bases than at their mouths, as clearly shown in Fig. 1.

The side portions of the mouth of each bucket 16 are contracted by means of oppositely disposed V-shaped plates 21, 22, which are secured to the end flanges 13, 14, respectively, as shown in Fig. 6.

By constructing the buckets 16 in the above described manner, when the drum 11 is rotated in the direction indicated by the arrow in Fig. 1, material or ore disposed in a lower bucket will be made to rise with the lower bucket to a considerable distance above the axis of the drum, and while thus rising will be crowded by the slanting sides 21, 22, toward the back of the bucket, occupying a central portion of the drum until it is finally discharged over the inner edge of the bucket as the latter assumes a horizontal position, and on further ascent changes to a downwardly inclined position. Due to the shape of the side walls of the bucket, the material, when the bucket reaches the discharging position, will occupy a central position and will drop through the center of the drum, that is that space between the end flanges 13, 14. In this way the material or ore discharged from a bucket will not spread outwardly sufficiently to fall through the openings in the end flanges 13, 14 of the drum 11.

Material or ore is delivered to the drum 11 from a feed hopper 25, located adjacent one end of the drum, as clearly shown in Fig. 3.

As shown, the drum 11 is rotatably supported in a cradle 27, comprising a pair of arcuate flexible members 28, 29 disposed underneath the drum and located, respectively, adjacent the two ends thereof.

For the purpose of supporting the cradle 27, I utilize a frame work 30 constructed preferably of structural steel and including uprights, 31, horizontal beams 32, and diagonal braces 33. The various parts of the frame work 30 may be formed from I-beams, channels, angle-irons and the like, as shown.

The frame work 30 is mounted on suitable supporting means, such as concrete posts or pillars 34 (see Figs. 1 and 2).

The flexible members 28, 29 comprise a chain-like structure composed of a series of bars or links 35 of suitable length. The adjoining ends of the bars or links are pivotally connected together by shafts 36.

Each shaft 36 also serves to support a pair of flanged wheels 37, which are disposed between the bars in the manner shown in Fig. 8.

The wheels 37 engage annular tires or tracks 38 mounted on the exterior of the wall 12 of the drum 11 and disposed adjacent the end flanges 13, 14.

As shown, the wheels 37 have a single flange, the flanges of each pair of wheels being so disposed as to engage the inner edges of the tires or tracks 38 as shown in Fig. 8.

The ends of the flexible members 28, 29 are anchored to rigid cross members 39 carried by the frame work 30, by means of blocks 40 and bolts 41. Interposed between the blocks 40 and the cross members 39 are resilient pads 44 formed of rubber or the like, which are adapted to absorb vibration and shocks transmitted by the drum 11 to the cradle 27.

In order to prevent undue lateral swinging 70 movement of the drum 11 and its cradle mounting, the intermediate bars or links 35 of the flexible members 28, 29 are formed with grooved or slotted portions 42, which are slidably mounted in uprights 43 projecting upwardly from the 75

foundation of the machine, as shown in Figs. 1 and 9.

For the purpose of rotating the drum 11, suitable driving mechanism is employed, said driving mechanism including an electric motor or other prime mover 45 and a flexible chain or other similar driving element 46, which is operatively connected to the drum 11 and in turn is adapted to be actuated by the motor 45.

10 The links of the chain 46 engage the teeth of a gear 47 arranged around the outer periphery of the drum 11, as shown in Fig. 2.

The chain 46 is in the form of an endless loop, one end of which passes around an idler 48 rotatably supported on a shaft 49 carried by the frame work 30, and the other end of which passes around a gear or sprocket 50 mounted on a shaft 51, also journaled in the frame work 30. As shown in Fig. 1, the chain 46 underlies and engages a sector of the drum 11 at one side of the machine.

20 The shaft 51 also has a large gear 52 mounted thereon, said gear being in meshing relationship with a pinion or small gear 53 carried by a shaft 54.

Shaft 54 also carries a large gear 55, which is operatively connected with the gear 56 of the motor 45, by a flexible element, such as a chain, V-belt, or the like 57.

30 In this way operation of the motor 45 will be transmitted through the power transmitting mechanism above described to the drum chain 46, at greatly reduced speed and the drum 11 will accordingly be rotated at a comparatively slow speed.

35 As shown in Figs. 1 and 9, the frame work 30 also serves as means for supporting two substantially semi-circular baffle plates 60. These baffle plates are respectively disposed adjacent each end of the drum 11, so that all the material dropping from the buckets 16, is confined to a central zone between the two baffle plates.

40 Extending through the drum 11 and supported from the baffle plates 60, are a plurality of impact means or breaker plates 61, which are located in the path of the material falling from the buckets 16:

45 Two of the breaker plates 61 are supported on I-beams 62, while the remaining breaker plates are mounted on saddles 63 supported from the baffle plates (see Figs. 1 and 9).

50 It will be noted that the breaker plates 61, I-beams 62, and saddles 63 are arranged at a slight angle to the horizontal plane, the angle being such that the dropping material which follows a curved path strikes the breaker plates 61 substantially at right angles.

55 It should also be noted that the breaker plates 61 are arranged in upper and lower series, the breaker plates of the lower series being arranged in staggered relation to those of the upper series.

60 At a suitable position above the breaker plate 61 at the extreme right hand side of the machine as viewed in Fig. 1, and also disposed adjacent to the ascending buckets 16, is a take-off grizzly 65.

65 The grizzly 65 may comprise a substantially rectangular plate which is sloped or set at an angle so that the outer or top edge which is close to the rising buckets, receives the material first discharged from the buckets. As shown in Fig. 1, the grizzly 65 slopes downwardly from a point adjacent the discharge edge of the buckets toward the center of the drum.

70 The grizzly 65 has a flat bottom 66, open upper

and lower ends, and opposite side walls 67. The side walls 67 are disposed adjacent the baffle plates 60, and at the lower end of the grizzly, the side walls 67 are formed with depending ears 69, which are pivotally connected to a frame, 5 as indicated at 70, Fig. 5.

The outer or higher portion of the bottom 66, of the grizzly is imperforate, while the inner or lower portion of the bottom is perforated, as indicated at 68, Figs. 4 and 5. The perforated 10 portion 68 of the grizzly constitutes a screen through which the fine material deposited on the grizzly can pass and thereby be separated from the coarser particles.

Underlying the grizzly 65 and preferably supported from the baffle plates 60, is a trough 71, the upper portion of which has an area corresponding substantially to the area of the perforated portion 68 of the grizzly so that the fine material which passes through the perforations 20 68, will be collected.

Leading from one end of the trough 71, is a launder or pipe 72, the purpose of which will be hereinafter more fully described.

The grizzly 65 normally rests on and is supported by the upper edge of the trough 71, as shown in Figs. 1 and 5.

The purpose of pivotally mounting the grizzly 65 is to permit upward swinging movement thereof in case any large pieces of material or other objects project beyond the discharge lip of an ascending bucket an amount sufficient to strike the outer portion of the grizzly. In such case, when the underside of the grizzly is engaged by material projecting from a bucket, the grizzly 35 will move upwardly about its pivots 70 and thus permit the upward passage of the obstruction without causing any damage to the bucket or the grizzly. As soon as the obstruction is removed and the bucket moves past the end of the grizzly, 40 the grizzly will drop back to its former position on the trough 71. In this way clogging of the machine at this point will be prevented.

Material falling out of the buckets onto the grizzly will be separated, the coarser particles 45 rolling down over the grizzly and dropping off the lower inner edge thereof, and the finer particles passing through the perforations 68 into the trough 71. The undersize or finer particles which pass through the screen provided by the perforated portion 68 of the grizzly, flow down the launder 72 and out of the machine.

If the screen openings of the grizzly 65 are of sufficient size, complete classification of the material may be accomplished at this point. However, since in most cases a fine product is desired and since such a fine product can only be obtained by employing a grizzly having a fine screen, it has been found by actual practice that the use of a grizzly having a fine screen is impracticable due to the unsatisfactory wearing qualities of a fine screen at this point. Therefore, it has been discovered that better results can be obtained by employing a grizzly having a comparatively coarse screen for the purpose of 65 separating the coarser particles from the fines and then further classifying the fines in order to separate the coarser particles therefrom and return the same to the machine for further reduction.

70 According to the present invention the fine material which passes through the screen 68 of the grizzly 65 is delivered by the launder 72 to a classifier device 75 located along one end of the drum 11. Any suitable type of classifier 75 may 75

be employed. In the present instance I have shown a classifier along the general lines of the rotary wet classifier shown in my Patent #1,917,-300 granted July 11, 1933.

- 5 The classifier 75 comprises an elongated drum 76 which is rotatably mounted on the frame work 30 heretofore referred to, said drum being set in an inclined position with its longitudinal axis at angle to the horizontal plane, as shown in Fig. 1.
- 10 The upper or higher end of the drum 76 is formed with a conical lip 77 over which the oversize material passes and is discharged into a trough or launder 78 leading to the interior of the drum 11, so that the oversize is returned to the machine 15 for further reduction.

At the lower or opposite end of the drum 76 there is an annular lip 79 over which the fines overflow and are delivered to a trough or launder 80 leading from the machine.

- 20 The launder 72 heretofore referred to projects into the upper end of the drum 76 a suitable distance, as shown in Fig. 1. The progress of material through the classifier 75 is such that the coarse or oversize material is carried toward the 25 discharge end at the right of the drum 76, as viewed in Fig. 1, and the fine material is carried out from the opposite end of the classifier by water overflowing therefrom.

As shown by the dotted lines in Fig. 1 the interior of the drum 76 is formed with screw flights 81, which urge the coarse material toward the upper or right hand end of the classifier.

For the purpose of rotating the classifier 75, roller treads 82, 83, Fig. 1, are provided which 35 rest upon pairs of rollers 84, 85, near the ends of the classifier. These rollers are mounted on shafts 86, 87, which are operated by a motor 88 and intermediate drive 89.

Since the description and operation of the classifier are fully described in the above mentioned 40 patent, no further explanation of the device is deemed necessary herein. It should be noted, however, that the classifier herein shown and referred to is of a type particularly suited for the 45 purpose of grading the product of the ore reducing machine so that the final product will be uniform and have the desired degree of fineness. It should also be noted that the location of the classifier 75 with respect to the grizzly 65 permits 50 gravity flow of the material from the machine to the classifier and gravity flow of the oversize material from the classifier back into the drum 11, and also gravity flow of the fines away from the classifier. In this way the cost of operating the 55 whole apparatus is reduced to a minimum.

In the operation of the device, material is fed 60 into the drum 11 from the hopper 25, the material falling into the buckets in the bottom of the drum. The buckets raise the material and gradually discharge the same for violent impact against the breaker plates 61 whereby the material is comminuted and made to gravitate from the breaker plates back to the buckets in the bottom of the drum 11.

In this connection it should be observed that 70 the dimensions of the drum of the machine are of great importance. It will be noted that as compared with drums used in ordinary cleaning or washing operations, the drums are of comparatively small diameter as compared with the length of the drum. In the present instance it is proposed to produce a distinct chipping action by the dropping of the ore on the breaker plates, and the drum 11 therefore is made of a diameter far in excess of that commonly employed, and as a mat-

10 ter of fact I find that a diameter of twenty feet or more is economically best suited for my purposes. If a drum of such diameter were made of the length of the drums usually employed in washing or grinding operations, it would be entirely unwieldy, and this is one of the reasons why I reduce the length of the drum to such an extent that the diameter of the drum is greatly in excess of the length, and the entire drum appears as being narrow, as compared with its diameter.

15 This construction is also advantageous in view of the fact that the drum works on principles altogether different from those controlling drums used in washing and grinding operations; in the latter the material is slowly advanced from one end to the other so as to be discharged from the end opposite to that which it entered. In my drum there is no such forward travel of the material, and as a matter of fact the material is continuously raised and dropped in the same plane until it is reduced to a size which allows it to be carried off as fines.

20 After the material has made impact with the breaker plates it drops into the buckets disposed in the bottom of the drum.

25 During operation of the machine the buckets 16 carry the entire load of the material within the drum with the exception of the small amount of material lying on the breaker plates 61 and the 30 material falling from the upper buckets.

With this in mind, as the buckets rise up from the bottom of the machine, each bucket will be filled with ore, with which is mixed a quantity of water.

35 Due to the shape and construction of the buckets the material carried therein during normal operation of the machine will not commence to spill from the buckets until after the buckets rise to a point above the axial center of the 40 drum 11.

45 As shown in Fig. 1, the grizzly 65 is located at a point above the center of the drum and below the point at which the material begins to spill from the buckets.

50 If the water and ore does spill below the grizzly, the machine becomes unstable in operation and is likely to become overloaded with a mixture of ore and water spilling back down the buckets. This condition increases wear and power with little or no increase in capacity of the machine, and is an undesirable method of operation. The location point of the grizzly 65 is therefore important, and when the grizzly is positioned as above described it improves and stabilizes the operation 55 of the machine to a marked degree as will be understood.

55 The coarse ore will drop on the grizzly, but will not pass out of the circuit unless the particles are small enough to pass through the perforations 68, but will slide over the grizzly and fall directly down into the bottom portion of the drum, striking on the way down the impact or breaker plates at the right hand side of the machine as viewed in Fig. 1. However, the greatest portion of the coarse particles of material, together with a certain quantity of fines that are embedded in the coarse pieces in the buckets, will be carried on past the grizzly 65 and drop on the breaker plates 61, where the crushing action takes place in the manner previously described.

60 The finer particles of the material together with the water which fall on the grizzly 65, will pass through the perforated portion 68 and into 70 75

the trough 11 and from thence will flow down the launder 72 to the classifier 75.

The finer particles together with the water which are delivered to the classifier 75 by the launder 72, are subjected to the classifying action whereby the coarser particles are returned to the drum 11 through the launder 78 and the fines carried away by the launder 80, as has been heretofore described.

From the foregoing it will be noted that by my invention I have provided an improved ore reducing machine in which means are provided within the drum of the machine for partially classifying the ground material and additional classifying means are provided outside of the drum 11 for the final classification of the material. In actual operation of a machine constructed according to my present invention the character of the product has been improved considerably over the products of other ore reducing machines heretofore in use, and due to the construction and arrangement of the parts and the manner of operating the classifiers, the amount of power consumption and the frictional wear on the interior of the drum of the machine has been reduced to a minimum, so that the machine can be successfully used for reducing lower grades of ore on a paying basis than would otherwise be possible.

Having thus described my invention what I claim and desire to secure by Letters Patent is:—

1. An ore reducing machine comprising a rotatable drum, impact means within the drum for receiving the thrust of the material, elevating means for lifting the material, and for discharging the same toward said impact means, a grizzly disposed above the impact means and located in the path of the material first discharged from the elevating means for classifying the material first discharged from the elevating means, means for supporting said grizzly, including pivots at one end of the grizzly and a rigidly mounted discharge trough for receiving the finer particles from the grizzly, and a launder leading from the discharge trough, the pivots permitting upward swinging movement of the grizzly in case the grizzly is struck by obstacles projecting outwardly from said material elevating means.

2. An ore reducing machine comprising a frame work, an arcuate cradle resiliently supported at each end by said frame work, a drum rotatably mounted in said cradle, means for rotating said drum comprising a flexible element operatively connected to the loaded side only of said drum, a source of power, speed reducing means operatively connecting said source of power and said flexible element; impact means within the drum for receiving the impact of the material undergoing reduction in the machine, elevating means on the drum for lifting the material and for discharging the material toward said impact means after the material has been elevated a predetermined height, means for intercepting the material first discharged from said elevating means and for classifying the material whereby the fines are separated from the coarser particles, means for removing the fines from the machine, means for returning the coarse particles to the machine for further reduction, means for classifying the fines removed from the machine so as to separate the same into fine and coarse particles, and means for returning the coarse particles from the second classifier to the drum for further reduction.

3. An ore reducing machine comprising a rotatable drum, impact means within the drum for receiving the thrust of the material, elevating means for lifting and discharging the material toward said impact means in a series of laterally descending streams, a stationary grizzly disposed above the impact means and located in the path of the portion of the descending stream of material first discharged from the elevating means, means formed on the grizzly for separating the fines from the coarser particles, and means for further classifying the fines separated by the grizzly and for returning the oversize portion thereof to the drum for further reduction.

4. In an ore reducing machine, the combination with a rotatable drum, of impact means mounted within the drum for receiving the impact of the material undergoing reduction in the drum, buckets carried by the drum for lifting the material and for discharging the material towards said impact means in a series of laterally descending streams after the material has been elevated a predetermined height, a screen for intercepting the material in the portion of the descending stream first discharged from the buckets and for classifying the material intercepted whereby the fines are separated from the coarser particles, means for removing the fines from the machine, and means for discharging the coarser particles from the screen toward said impact means for further reduction.

5. In combination, a breaker medium, a drum having buckets for elevating material and for dropping the same on the breaker medium in a series of laterally descending streams, stationary screening means located in the path of the portion of the descending stream of material first discharged from the buckets for intercepting such material and for screening the same to separate the finer particles from the coarse, means located without the drum and operatively associated with said screening means for receiving the fines passing through the screening means and for classifying the same whereby the coarser particles are separated from the fines, and a launder leading from said classifying means to the interior of the drum for returning the coarser particles of the classified material to the drum for further reduction.

6. An ore reducing machine comprising a crushing chamber adapted to receive ore therein, means within the chamber for raising and dropping the ore in a series of laterally descending streams, an impact medium in the lower portion of the chamber for receiving the dropping ore, stationary screening means located in the path of the portion of the descending stream of ore first discharged from the ore raising means for intercepting such material and for screening the same to separate the finer particles from the coarse, means for returning the coarser particles to the crushing chamber, means located without the crushing chamber and operatively associated with said screening means for receiving the fines passing through the screening means and for classifying the same whereby the coarser particles are separated from the fines, and means connecting said last named classifying means with the interior of the drum for returning to the drum the coarser particles of the classified ore for further reduction.
